CLAIM

The ornamental design for a glass cross as shown and described.

DESCRIPTION

FIG. 1 is a right side perspective view of a glass cross, showing my new design;

FIG. 2 is a left side perspective view thereof;

FIG. 3 is a front elevational view thereof;

FIG. 4 is a left elevational view thereof, the right elevational view being a mirror image of FIG. 4;

FIG. 5 is a top plan view thereof; and,

FIG. 6 is a bottom plan view thereof.

The broken lines in the figures are for the purposes of illustrating portions of the glass cross, which form no part of the claimed design.

1 Claim, 5 Drawing Sheets
